METHOD OF AND APPARATUS FOR SEPARATING MATERIALS OF DIFFERENT SPECIFIC GRAVITIES

Application filed August 22, 1931. Serial No. 558,812.

My invention relates to methods of and apparatus for separating materials of different specific gravities. The invention pertains more particularly to methods of and apparatus for classifying and separating coal or other minerals, in which mixtures of the materials of different specific gravities are subjected in a water-immersion as a fluid mass to hydraulic action and preferably also mechanical agitation effecting classification and separation of the materials.

With prior art methods and apparatus of the general type to which my invention pertains, the separation of materials of substantially different specific gravities has offered little difficulty. But where material of intermediate specific gravity is also present in the mixture, and especially where it is of a specific gravity closely approaching that of the material of value to be separated from the other materials as impurities, the separation is attended with difficulty. This is due to the tendency of the material of the intermediate specific gravity to go with the material of value, or, when particular steps or means are employed to separate out the material of the intermediate specific gravity with the other materials of the reject, to the tendency of the material of value to be also carried along so that much of it is lost in the reject.

The foregoing difficulties are well illustrated in the case of the separation of coal from its impurities which generally are a very poor grade of coal called "boney", and rock, pyrites, slate and the like, commonly designated simply as slate. The material of value, the high grade coal, is of the lowest specific gravity, the slate materials are of the highest specific gravity, and the "bony" is the material of the intermediate specific gravity. In methods and apparatus employing an up-flowing current of water for the stratification of the materials according to their different specific gravities, generally the good coal which is to be separated out as the material of value is floated off into a discharge at the top of the liquid column, and the materials of intermediate and higher specific gravities are separated out at the bottom. But with

all such methods and apparatus of the prior art, so far as I am aware, the separation is not sufficiently well defined to give the greatest possible recovery of the high grade coal. Either the lighter impurities, such as the "bony", are carried over into the discharge with the high grade coal or much of the high grade coal is carried along with the settling and discharge of the "bony" or other impurities and wasted in the reject.

One reason why these defects are not overcome or avoided in these prior art methods and apparatus is the substantially unvaried condition of the fluid medium in which settling stratification of the materials occur according to their different specific gravities. For example, with methods and apparatus employing an upwardly flowing current of water for the floating off and discharge of the high grade coal at the top and the settling of the heavier materials through the column of liquid, the lighter refuse material tends to so accumulate immediately beneath the stratum of coal at the top as to be forced over to some substantial extent with the coal into the discharge.

This particular defect can be avoided by substantially reducing the velocity of the upward flow of the water so as to give but slightly hindered or practically free settling of these impurities. But upon such reduction there is a tendency for all the materials to settle through the column of liquid at so comparatively rapid a rate that the operator soon finds good coal appearing with the reject material. One defect is thus overcome simply to introduce another, for it is impossible by manual control based upon observation of the materials discharged at the value and reject ends of the apparatus to maintain the proper balance eliminating both of the referred-to defects.

Other methods and apparatus of the prior art employ a suspension in the water column of finely divided solid particles, such as sand for example, of specific gravity greater than that of the high grade coal and most of the impurities to be separated therefrom, with the mixture mechanically or hydraulically agitated to maintain the suspension. In this

denser fluid medium employed for the stratification and separation out of the materials, the material of value, for example the high grade coal, floats at the top and the 5 heavier impurities settle through the fluid mass at varying rates according to their varying specific gravities. Some appreciable hydraulic head and current flow is, of course, still employed to discharge the value coal at 10 the top of the column. There is therefore still some tendency to the discharge with the value coal of some of the accumulated lighter impurities near the top of the column, and the discharge of some of the value coal with 15 the reject if the hydraulic conditions are changed sufficiently to entirely eliminate the first-mentioned defect; for example, by reducing the upward flow of the water or the agitation of the fluid mass upon observation 20 of the materials discharged at the reject end of the apparatus.

Accordingly, a primary object of my invention is to provide a method and apparatus of the general type of these prior art methods 25 and apparatus but which will be free from their defects referred to above.

In other words, the general object of my invention is to provide a method and apparatus by which coal or other minerals may 30 be separated from their mixtures substantially free from the impurities usually found mixed therewith.

As in the prior art methods and apparatus briefly referred to above, my invention employs a body or column of liquid, such as 35 water, for the classification by settling of the materials of the mixture fed thereto. Preferably nothing is added to the liquid except the materials of the mixture fed there- 40 to so that the fluid mass preferably consists only of the body of liquid and those materials.

As in the prior art methods and apparatus, so also with the method and apparatus of my 45 invention, the hydraulic state of the liquid column or of the entire fluid mass (that is, its state or condition of motion) has an effect on the settling of the materials therein.

To attain its object referred to above, my 50 invention contemplates changes in the hydraulic state of the fluid medium effecting the settling, in accordance with changes of its density due to stratification of materials therein and settling out of materials there- 55 from, so decreasing the resistance to downward settling when the density increases as to prevent material of the intermediate specific gravity from accumulating so near the top of the column as to go over into the 60 discharge with the material of the lowest specific gravity, and so increasing the resistance to downward settling when the density is decreased as to prevent the settling of the material of the lowest specific gravity with 65 the other materials to a common discharge.

While not necessarily limited thereto, my invention preferably employs a variation in the liquid upflow in the classification or sorting column as the factor producing the changes referred to in the hydraulic state of the fluid medium effecting the classification and settling, a lessening of the velocity of upflow being employed to decrease the resistance offered by the fluid body to downward settling of the materials and an increase of the 75 velocity of upflow being employed to increase that resistance.

Preferably also the changes in the liquid upflow contemplated by my invention are such as to produce an intermittent substantially free and hindered settling of the materials fed to the sorting column. For the hindered settling, the upward flow of the liquid is at a predetermined maximum velocity designed to float the material of the lowest specific gravity off into the discharge at the top of the column while permitting the ready downward settling therefrom of the materials of substantially higher specific gravity. Under this hindered settling, material of an intermediate specific gravity fairly closely approaching that of the lightest material tends to stratify out near the top of the column until the density of this stratum becomes such that, if the hindered settling were continued, more or less of this material would be forced by the current upflow over with the lightest material into the discharge at the top of the column. To avoid this, the substantially free settling, by reduction in the upward current flow, is brought about through the increased density of the fluid mass as a controlling factor. The substantially free settling, of course, rapidly reduces the density of the fluid mass, and if it were continued the lightest material would be carried down with the heavier to a common discharge. To avoid this, the hindered settling, by restoration of the original upward current flow, is brought about through the decreased density of the fluid mass as the controlling factor.

To make the density of the fluid mass the controlling factor in the changes just referred to, my invention preferably employs means responsive to variations in resistance to the upward flow of the liquid offered by the material itself as it varies in density in the classification or sorting column. One convenient form such means may take comprises a water-expansion chamber in communication with the sorting column and with associated mechanism controlled by the rise and fall of the liquid in that chamber for operating valve means determining the upward flow of the liquid in the sorting column. With such an arrangement, as the density of the fluid mass in the sorting column increases and thereby greater resistance is presented to the upflow of the water, that water backs up

into the water expansion chamber and the rising water therein is utilized to operate the valve means to reduce the original upflow current in the sorting column so as to bring about a less hindered or substantially free settling condition. Likewise, as the density of the fluid mass in the sorting column decreases and thereby less resistance is offered to the upflow of the water, the water backed up in the water-expansion chamber returns to the sorting column and the lowering water in the chamber is utilized to operate the valve means for restoration of the original upflow current in the sorting column giving the hindered settling.

The foregoing and other objects and advantages of my invention and its operating principles both as to the method and apparatus and the structural principles of the invention as to the apparatus will more fully appear from the following concrete examples. It is to be understood, however, that while these examples present one mode of practicing the method and one form of apparatus of my invention found particularly desirable, the invention is not limited thereto, and that it includes other modes of practicing the method and other forms and constructions of the apparatus within the scope of the appended claims.

In the drawings, which are somewhat diagrammatical:

Fig. 1 is a top plan view of one form of the apparatus of my invention;

Fig. 2 is in part a side elevation and in part a vertical sectional view of that apparatus along the line 2—2 of Fig. 1, and showing the materials therein under the condition of maximum hindered settling;

Fig. 3 is a cross sectional view, on an enlarged scale, along the line 3—3 of Fig. 2, and showing a perforated plate employed in the lower portion of the sorting column or tank of the apparatus;

Fig. 4 is a view of the apparatus identical with Fig. 2, but showing the materials therein under the condition giving a freer settling than represented in Fig. 2;

Fig. 5 is a vertical side-elevational view, on a larger scale than that of Figs. 2 and 4, of the upper portion of the float-chamber of the apparatus, with an adjustable bracket on the upper end of that chamber forming a part of mechanism for adjustably controlling the upflow of water in the sorting column;

Fig. 6 is a view of the same parts of the apparatus shown in Fig. 5, but at a right angle thereto;

Fig. 7 is a side-elevational view, on a larger scale than that of Figs. 2 and 4, of the disc of the valve controlling the upflow of water in the sorting column, and of an adjustable connection between the valve disc and the solenoid employed to operate the valve; and

Fig. 8 is a view of the same parts of the apparatus shown in Fig. 7 but at a right angle thereto.

The illustrated apparatus is of a form especially adapted for the separation of coal from its impurities, though it may be used also for the separation of other minerals. Since the method and apparatus of my invention as applied to the separation of coal from its impurities involves substantially the same principles as when applied to the separation of other minerals, the present description will be confined to the separation of coal as a typical instance of use serving to present the essential principles of the invention.

The particular form of apparatus embodying my invention which is shown in the drawings includes a main receptacle or tank so supplied with water as to function as a classification or sorting body or column for the coal mixture fed thereto. In the form as shown, this tank has a cylindrical upper portion 1, an intermediate portion 2 of an inverted cone shape with its walls converging downwardly to a tubular lower portion 3 of a substantially lesser diameter than that of the uppermost portion. This lower tubular portion or member 3 of the classification or sorting tank communicates with and rises from a chamber 4 through which the water for the sorting column is supplied in the manner hereinafter more fully set forth.

The chamber 4, together with an extension 5 extending obliquely upward to an open end, also forms a combined water-expansion chamber and conveyor boot, one function of which is to receive from the sorting column the refuse materials settling downward therethrough and to convey them away from the apparatus.

As the conveyor, indicated by the numeral 6, is the usual flight conveyor of well known construction, it is sufficient to here state that its receiving end is journaled in the bottom portion of the chamber 4 in the line of discharge of the refuse material through the tubular portion 3 of the sorting tank, and its delivery end extends beyond the upper open end of the boot in which it is located. It is operated by a head shaft 7 adjustably mounted in the brackets 8, which shaft may be driven by any suitable means.

Means are preferably employed for agitating the fluid mass in the sorting tank. For that purpose, in the illustrated apparatus, that tank is provided with mechanical agitating means comprising a series of rotating blades 9 driven by shaft 10 upon which they are mounted, the shaft 10 being suitably mounted as shown to extend axially within the tank and thereabove so as to be rotated by the gears 11 and 12 which in turn may be driven by any suitable means.

The coal mixture which makes up the feed to the apparatus in its illustrated use is de-

livered to the sorting or classification tank from a traveling conveyor of the usual type through a chute 13, the delivery-end portion 14 of which is of conical form and disposed 5 concentrically of the tank so as to feed the materials centrally thereto.

Provision for the discharge at the top of the sorting column of low specific gravity material in the mixture is made by way of 10 a circular launder 15 surrounding the tank and a chute 16 through which the discharged material is delivered to a vibratory screen 17 through which the water is drained as the material travels thereover to a final line of 15 discharge from the apparatus indicated at 19.

Any suitable means may be employed for imparting vibratory movement to the screen. As shown somewhat diagrammatically, the screen 17 is suspended by spring 20 boards 20 from the cross piece 21 of the apparatus frame and is oscillated or vibrated by a board and eccentric 22 operated from the shaft 23.

One of the desirable features of the apparatus 25 is the provision of a constant static head for the supply of water to the sorting or classification tank to form the liquid column therein. In the illustrated apparatus, this takes the form of an overhead receptacle 30 or static head tank 24 supplied by a fresh water pipe 25 having a valve 26 automatically controlled in the well known manner by a float 27 in the tank 24, as more or less diagrammatically indicated on the drawings. 35 Water is supplied under pressure from this tank 24 through piping 28 and valve therein to the water expansion chamber 4, the valve being indicated in Figs. 2 and 4 by the disc 29 on its stem.

40 To conserve the water drained from the material advancing over the screen 17, a drainage receptacle 30 is mounted on the frame of the apparatus immediately beneath the screen, and from this receptacle the water 45 is returned by the pump 31 through the pipe 32 to the overhead tank 24.

Any suitable source of power and power-transmission means may be employed to drive the flight elevator 6, the shaft 10 of the agitator, the screen 17 in its vibratory movement and the pump 31. As shown diagrammatically, an electric motor 33 is employed to drive these parts through belt and chain drives 34 as required.

55 An even distribution of the uprising current of water entering the main tank for the settling and classification operations is desirable; and as a means therefor the plate 35 with numerous uniformly distributed openings 36 therethrough, as shown on an enlarged scale in Fig. 3, is provided within the tubular lower portion 3 of the sorting tank.

With the valve 29 rotated to its maximum open position, the water supplied through 60 pipe 28 under its constant static head to the

receiving side of this valve is admitted therethrough to the chamber 4 of the apparatus in maximum volume to produce a maximum velocity flow of the water from the chamber 4 upwardly into the tubular member 3 of the 70 sorting tank, through the openings 36 of the plate 35 therein, and therefrom upwardly through the remainder of the tank to overflow into the launder at the top thereof. This maximum velocity flow of water through the 75 perforated plate produces a hindered settling classification of the materials fed to the tank. The plate 35 with the numerous openings 36 uniformly distributed over its area functions to maintain an even distribution of 80 the uprising currents which produce the hindered settling as the plate presents sufficient resistance to the upward flow of the water through the tubular member 3 to maintain a uniform distribution of the water entering 85 the sorting tank regardless of the inequalities in the distribution of materials through the fluid mass above the plate or inequalities in the water pressure or velocity on the under side of the plate due to frictional resistance 90 of the water on the lower wall of the tubular member of the tank.

The coal mixture having been delivered to the center of the tank, mixes with the agitated water to form a fluid mass, at first thin but 95 gradually thickening as the mass forms into a stratified mobile body under the hindered settling. The heavy material, such as slate, settles fairly rapidly entirely through the fluid mass and into the chamber 4 where it is 100 received by the conveyor 6 and carried away as refuse. The purer or better grades of coal within the fluid mass, as the material of lowest specific gravity, assume under the hindered settling an uppermost position, and as 105 it accumulates it is carried over by the upwardly flowing water into the launder 15 as value material. Other materials of intermediate specific gravity, such as the "bony" or like impurities which are to be rejected as 110 refuse, stratify out beneath the layer of good coal instead of dropping through with the slate. As this material accumulates, if the maximum velocity of the upward current of water were maintained, more or less of it 115 would be forced over by the upflowing current with the good coal into the discharge with the value material at the top of the column.

To avoid the foregoing defect, as hereinbefore stated, my invention contemplates means to automatically reduce the velocity of the upflow of water in the sorting column as the density of the material accumulating therein increases, that reduction of 120 course reducing the resistance to settling and thereby enabling the accumulated "bony" or like refuse material to settle downwardly from the discharge at the top of the column, and then to restore the original maximum 125

velocity of current upflow to avoid the discharge of the good coal downwardly with the refuse.

In the form of apparatus shown in the drawings, the means for controllably regulating the velocity of the upward current flow of water in the sorting tank so as to produce the variably hindered settling or the intermittent hindered and substantially free settling, includes an electric solenoid 37. This solenoid has its core connected through a rod 38 to the disc 29 on the stem of the rotatable valve which controls the flow of water to the sorting tank so as to partially rotate or oscillate that valve in the opening and closing directions to the extent determined upon for the desired maximum and minimum upward current flow of water in the sorting tank.

Desirably, means may be employed for an adjustable setting of the valve in respect to its maximum and minimum open positions when operated by the solenoid. One form such means may take is shown in Figs. 7 and 8. As there shown, the disc 29 is provided 25 with two circular series of holes 29' and 29" at different distances from the valve stem or axis of rotation of the disc, and one end of the rod 38 may be removably secured to the disc in the location of any one of these holes 30 by the bolt-and-nut attachment 38', with the bolt passing through the selected hole in the valve disc and through the apertured head of the rod, as shown more particularly in Fig. 8. The other end or foot of the rod 38 35 is pivoted to the core of the solenoid and the rod is formed as a divided or two-part rod with a turnbuckle 38" intermediate its ends for adjustment of the length of the rod and consequently of the length of the connection 40 between the valve disc and the core of the solenoid to accommodate the initial angular setting of the valve for the desired maximum and minimum open positions of the valve upon the upward and downward stroke of 45 the core of the solenoid.

Fig. 2 indicates the opened position of the water-control valve 29 to the extent determined upon for the maximum velocity of upward flow of water in the sorting tank and 50 Fig. 4 indicates the extent of movement toward closed position for the minimum velocity.

The electric solenoid is actuated by float 39 riding on the surface of the water in chamber 40 which chamber is in open communication at its lower end with the extension 5 of the water chamber 4, so that the chamber 40 is a part of the water-expansion chamber. As shown more or less diagrammatically in 55 Figs. 2 and 4, the upper and lower terminals 41 and 42 of the solenoid circuit and the bridge bar 43 on the stem of the float function as a switch for directing the current through the solenoid in opposite directions 60 for its two-way operation in oscillating the

water-control valve 29. When the water rises sufficiently in the float chamber for the float to elevate the bridge bar 43 into contact with the upper terminals 41, the solenoid is energized to oscillate the water-control 70 valve 29 to the partially closed position shown in Fig. 4; and when the water falls sufficiently in the float chamber for the float to lower the bridge bar into contact with the lower terminals 42, the solenoid is energized 75 to oscillate the valve 29 from its position shown in Fig. 4 to its more open position shown in Fig. 2.

Other means for the automatic operation of the water-control valve 29 may be employed such, for example, as a large float connected to the valve stem through a system of mechanical levers or the use of hydraulic or pneumatic systems to actuate the valve to any desired extent when the float is 80 raised or lowered by the changing water level in the float chamber.

The apparatus is shown in Figs. 2 and 4 as used in the performance of the method of my invention. Fig. 2 illustrates the condition of the fluid mass in the classification or sorting tank when there has accumulated therein, under the maximum velocity of water upflow and consequently hindered settling, a large percentage of relatively light 95 refuse, the top of which is coming relatively close to but is yet within a safe distance from the overflow point of the desired quality of clean coal. It is to be noted that Fig. 2 represents the water-control valve 29 open to its 100 maximum position as determined by the operation of the solenoid and the initial setting of the valve on the connections between it and the solenoid whereby a maximum velocity of the upward current of water through the lower tubular portion 3 of the sorting tank and the perforated plate 35 therein is created.

This maximum velocity of upward flow of water in the sorting tank presents the maximum resistance to the downward fall or settling of the particles of refuse and results in only the heavier ones dropping through the perforated plate 35 and on to the receiving end of the conveyor 6 in the chamber 4. With the valve in this maximum open position as shown in Fig. 2, therefore, the fluid mass accumulates a large percentage of particles having an intermediate specific gravity between that of the pure coal and the heavy refuse until this stratum of material becomes so 115 dense as to substantially increase the resistance to the upward flow of water through the mass and consequently increases the head of water in the water expansion chamber 4-5 and the communicating float chamber 40.

The foregoing condition is represented in Fig. 2 in which the fluid mass in the sorting tank is represented as relatively much denser and the height of the intermediate-specific gravity material nearer to the overflow point 120 125 130

of the good coal than represented in Fig. 4 which is intended to show the conditions under the less hindered or substantially free settling. In each of these views the particles 5 of good coal, as the material of lowest specific gravity, are represented in solid black, while the particles of the refuse are represented in outline with a clear center.

With the conditions of the maximum hindered settling described above and the water 10 in the float chamber gradually rising, Fig. 2 illustrates the float switch about to make the contact, with the upward terminals 41, which will actuate the solenoid 37 to oscillate the 15 water-control valve 29 to its minimum open position shown in Fig. 4. When this contact and actuation of the valve occurs, the velocity of the upward flow of water through tube 3 and perforated plate 35 of the sorting 20 tank is reduced to a minimum, with a corresponding reduction in the resistance offered by the water to the downward falling or settling of the particles of material undergoing 25 classification. The result is that the material of the intermediate specific gravity as well as the heavier drops through the perforated plate in the bottom portion of the sorting tank into the chamber 4 and upon the receiving end of the refuse conveyor therein, 30 so that the danger of the material of intermediate specific gravity going over with the good coal into the discharge at the top of the column is avoided.

With the valve 29 in this minimum open 35 position as represented in Fig. 4, the fluid mass in the settling tank gradually becomes less dense due to the dropping out therefrom of the particles having an intermediate specific gravity between that of the pure coal 40 and the heavy refuse. This lessened density as well as lowering of the intermediate specific gravity material substantially below the level of the discharge for the good coal at the top of the column is shown on Fig. 4 as compared 45 with Fig. 2.

As the material of the intermediate specific gravity thus drops out of the fluid mass in the sorting column, that mass because of its lessened density offers less resistance to the upward flow of the water in the sorting tank and as a consequence the head of water in the float chamber 40 decreases. The water level in the float chamber therefore gradually lowers, Fig. 4 illustrating the float switch about to 50 make the contact, with the lower terminals 42, which will actuate the solenoid 37, in the reverse direction to the original first-mentioned actuation, to oscillate the water-control valve 29 again to its maximum open position shown 55 in Fig. 2. When this occurs the maximum velocity upward flow of water to the settling chamber is restored to again produce the hindered settling.

It is sometimes desirable to adjust the 60 position of the terminals of the float switch.

As a convenient arrangement for this, the bracket 44 in which the upper and lower terminals 41 and 42 of the solenoid circuit are mounted may itself be mounted for lengthwise adjustment on the upper-end portion of the float chamber 40; for example, by an ordinary slot and bolt mounting, so that the height of these terminals with respect to the observed upper and lower ranges of the water level can be adjusted. Such a mounting is shown in Figs. 5 and 6, the bracket 44 having an elongated slot 45 in each of its opposite sides, and the upper end portion of the float chamber 40 being suitably apertured, for the insertions of bolts 46 through the cylindrical wall of the chamber and the slots in the bracket, nuts on the outer projecting ends of the bolts then removably securing the attachment. Obviously all that is needed for an up or down adjustment of the bracket is the loosening of the nuts and the sliding of the bracket on the bolts to the desired position, and the new adjustment is then secured by tightening the nuts. Also, as shown, the cross supports for the upper and lower contacts 41 and 42 are secured by bolts passing through the slots in the bracket and therefore these contacts are also vertically adjustable in the bracket. This adjustability of the terminals with respect to the water level in the float chamber 40 permits a variation in the control of the water valve 29 in respect to the control factor of density of the fluid mass in the settling chamber. For example, it may be found that with 100 the terminals set at a certain height the bridge bar 43 of the float stem does not make contact with the upper terminals 41 of the solenoid circuit until the density of the fluid mass in the sorting chamber has reached the 105 point causing the upflow current of water to force some of the lighter refuse over with the good coal into the discharge at the top of the column. To correct this defect, these terminals may be lowered to cause the contact to be made when a lesser density of the fluid mass in the sorting column is reached. Likewise, during the condition of less hindered settling resulting from the reduction 110 in the velocity of the upflow of water in the sorting column, it may be found that the bridge contact bar 43 of the float stem does not make contact with the lower terminals 42 of the solenoid circuit to restore the maximum velocity of the upward flow of water 115 and the consequent hindered settling before the density of the fluid mass in the sorting tank has been so decreased that some of the good coal settles downwardly with the refuse to the discharge at the bottom. Then the height of the terminals may be adjusted 120 to cause that contact at a sufficiently higher density of the fluid mass to avoid the defect. All this is of course possible because the float chamber functions as a balancing column in 130

the sense that the height of the water level therein is responsive to the resistance offered by the fluid mass in the sorting column to the upflow of water, which resistance in turn depends upon the density of the fluid mass.

It is thus clear that the illustrated apparatus may be so used that before the good coal gets anywhere near a point in the sorting tank rendering it possible for that coal to get into the reject, the float switch comes into operation to open the water-control valve to an extent restoring the hindered settling and preventing any possible leak of the good coal into the reject. Also, before the intermediate-specific-gravity material gets near enough to the top of the sorting column to render it possible for that material to be forced over by the upflowing water into the value discharge with the good coal at the top of the column, the float switch again comes into operation to move the water-control valve toward its closed position sufficiently to bring about the freer settling which immediately lowers the refuse material away from the coal discharge and thereby absolutely prevents impurities from getting into the good coal.

It is also apparent that the operating connections between the solenoid core and the stem of the water-control valve 29 permits an angular adjustment of that valve with respect to the solenoid which operates it, so that the valve may be adjustably set for any desired maximum and minimum open position when operated by the solenoid. Thus the maximum and minimum velocity of upward flow of water in the settling tank may be adjustably determined.

With perhaps most coal mixtures, the setting of the water-control valve should be such that when operated by the solenoid in the manner described the maximum and minimum open positions give respectively a hindered and a substantially free settling to avoid forcing the lighter refuse over with the good coal into the discharge at the top of the column. With other mixtures, substantially free settling may not be required but rather a less hindered settling than obtains with the maximum open position of the water-control valve, so that the condition required is a variably hindered settling.

In the foregoing description, the expression "substantially free settling" is employed as meaning such a reduction in the velocity of the upward flow of water in the sorting or classification tank as to present no substantial resistance by the water to the downward settling of the materials. As already stated, the water-control valve is operated back and forth by the solenoid between adjustably set maximum and minimum open positions, which means, of course, that the upflow of water through the sorting tank is continuous but changes in velocity between

the two extremes of maximum and minimum as determined by the settling of the valve. At the minimum as well as the maximum velocity of the upflowing current there is, as hereinbefore stated, a settling out of the heaviest materials downwardly of the sorting column to the conveyor, at the maximum velocity the materials of intermediate specific gravity tend to accumulate in strata immediately below the good coal as the material of lowest specific gravity at the top and at the minimum velocity of the upward current this material of the intermediate specific gravity settles downwardly to the discharge at the bottom. Preferably the minimum velocity of the upflowing current through the body of liquid in the sorting column is such as to still sustain the materials of the lowest specific gravity, in this instance the good coal, in the body of the liquid in the sorting column, but to avoid the tendency of some of that material to be physically carried downwardly with the materials of the intermediate specific gravity to the refuse discharge the change is made from minimum back to maximum upward current flow.

Only one water-supply pipe is shown in the drawings, the pipe 28 leading to the chamber 4 at the bottom of the tank but it will be understood that the sorting tank may be provided with one or more valve-controlled water-supply pipes for additional water found desirable in maintaining the proper fluidity of the contents of the tank.

In the use of the method and apparatus for the separation of coal from its impurities, the coal mixture is preferably sized before being subjected to the classification and separation treatment.

What is claimed is:

1. A method of separating materials of at least two different specific gravities from a mixture containing them which comprises feeding said mixture to a column of water, effecting such an hydraulic state of said column by movement of the water therein as to produce a hindered settling of the materials of the second lowest specific gravity in said column and a floating of the materials of the lowest specific gravity thereabove to a position of discharge, and so changing the hydraulic state of said column by reduction of the movement of the water therein as the density of the fluid mass in the column increases as to produce a sufficiently free settling to prevent the materials of said second lowest specific gravity from being discharged with the materials of the lowest specific gravity.

2. A method of separating materials of at least two different specific gravities from a mixture containing them which comprises feeding said mixture to a water-sorting column, effecting such an hydraulic state of said column by uniformly distributed currents

- therein as to produce a hindered settling stratifying the material of the next lowest specific gravity near the top of the column and floating the material of the lowest specific gravity thereabove off to a discharge from the column and as the density of said fluid mass increases due to said settling so changing the hydraulic state of said column effecting the settling as to prevent the accumulation of said material of the next lowest specific gravity near enough to the top of the column to cause its discharge with the material of the lowest specific gravity.
3. A method of separating materials of at least two different specific gravities from a mixture containing them which comprises feeding said mixture to a column of water, effecting such an hydraulic state of said column by movement of the water therein as to produce a hindered settling of the materials of the lowest and next lowest specific gravities stratifying said materials in the order of their specific gravities near the top of said column with the materials of the lowest specific gravity floating upon the stratum of the other material in a manner to discharge material from the upper stratum over the rim of the column and as the density of the bottom stratum increases due to said hindered settling so changing the hydraulic state of said column as to produce a sufficiently free settling to lower said bottom stratum below the point of possible discharge of material therefrom over the rim of the column.
4. A method of separating materials of at least two different specific gravities from a mixture containing them which comprises feeding said mixture to a column of water with which it forms a fluid mass, effecting movement of the water through said fluid mass in a manner to produce a hindered settling stratifying the materials of the lowest and next lowest specific gravities in the column with the lightest material uppermost in a position to discharge over the rim of the column and as the density of the bottom stratum increases due to said hindered settling so reducing the movement of the water through said mass as to produce a sufficiently free settling to drop material from said bottom stratum through the column to a bottom discharge and as the density of said fluid mass is thus decreased restoring the hindered settling so as to thereby prevent a sufficient accumulation under the hindered settling of said material of the next lowest specific gravity to overflow the rim of the column and to prevent under the freer settling the discharge of material of the lowest specific gravity with that of the next lowest specific gravity at the bottom of the column.
5. A method of separating materials of different specific gravities from a mixture containing them which comprises subjecting said mixture with water as a fluid mass in a suit-

able container to a current of water through said fluid mass of such direction and velocity as to cause the heaviest materials to settle to a point of discharge, the lightest material of said mixture to be carried along to another point of discharge and the material of intermediate weight to be suspended between said points of discharge, and as the density of said fluid mass increases due to accumulation of said last-mentioned material in suspension decreasing the velocity of said current to settle said last-mentioned material to a point of discharge other than the point of discharge for said lightest material.

6. A method of separating coal or other mineral of lower specific gravity than the materials mixed therewith comprising subjecting the mixture in a sorting column to a rising current of water of a velocity causing the coal to overflow the rim of the column and the heavy material to settle downwardly through the column to a lower discharge and upon accumulation of material of an intermediate specific gravity in said column to a density approaching that sufficient to cause its discharge by said current over the rim of the column decreasing the velocity of said current sufficiently to cause settling of said intermediate-specific-gravity material downwardly in said column, and restoring the initial velocity of said current before the density of the contents of said column has been decreased sufficiently by said last-mentioned settling to permit settling of the coal or other mineral to said lower discharge.

7. A method of separating coal or other minerals of lower specific gravity than the materials mixed therewith comprising subjecting the mixture in a sorting column to a rising current of water at all times of insufficient velocity to prevent the settling of the heaviest material downwardly through said column to a discharge at the bottom, and varying the velocity of said current from a maximum to a minimum and back again to the maximum in recurring cycles in such correspondence with increase and decrease of density of the materials accumulated in said column as to cause the maximum velocity current to stratify material of an intermediate specific gravity in said column and the coal to overflow the rim of said column and to cause the minimum velocity current to settle said intermediate-specific-gravity material downwardly before it has accumulated to a density sufficient to overflow the rim of the column and as to cause the restoration of the maximum velocity current before the decrease in density due to the last-mentioned downward settling has become such as to settle the coal downwardly to the bottom discharge.

8. A method of separating coal or other mineral of lower specific gravity than the materials mixed therewith comprising subject-

ing the mixture with water as a fluid mass in a suitable container to mechanical and hydraulic agitation permitting settling of the material of heaviest specific gravity down-
5 wardly in said container to a bottom discharge but maintaining the other materials in suspension and floating off the mineral over the rim of said container and upon increase in density of said suspended material reduc-
10 ing the hydraulic agitation while continuing the mechanical agitation to prevent discharge over the rim of the container of material other than the coal or other mineral.

9. A method of separating coal or other mineral of lower specific gravity than the materials mixed therewith comprising feeding said mixture to a body of water in a sorting column, mechanically agitating said water and materials to form a fluid mass, causing an upward current of the water in said sorting column to classify the mineral and float off the same over the rim of the column, reducing the velocity of said upward current as the density of said fluid mass increases and increasing the velocity of said current as the density of said fluid mass decreases so as to prevent discharge of material other than said mineral over the rim of said column and settling of the mineral with other material to a common discharge below the rim of said column.

10. An apparatus for the classification and separation of materials of different specific gravities comprising, in combination, a water-containing sorting column having a lower and an upper discharge for classified materials, means for feeding a mixture of said materials to said sorting column and for maintaining the mixture with the water as a fluid mass with the materials freely movable in the body of water throughout the sorting column, means for agitating said fluid mass to an extent producing a hindered settling causing the material of the lowest specific gravity to assume a position in said sorting column in delivery relation to said upper discharge, permitting settling of material of the heaviest specific gravity downwardly to said lower discharge and accumulating material of an intermediate specific gravity in said sorting column below said upper discharge, and automatically operating means for intermittently decreasing and restoring said agitation of the fluid mass to correspondingly decrease and restore the original resistance to downward settling upon increase and decrease in density of said fluid mass in said sorting column and so responsive to changes in density as to prevent the accumulation of said intermediate-specific-gravity material in said column to an extent bringing it into delivery relation with said upper discharge and as to prevent the settling of the material of the lowest specific gravity downwardly to said lower discharge.

11. An apparatus as set forth in claim 10 and in which the means for agitating said fluid mass comprises means for hydraulically agitating said fluid mass.

12. An apparatus for the separation of materials of different specific gravities comprising, in combination, a sorting column having discharges at different levels for classified materials, means for feeding a mixture of said materials to said column, means for maintaining an upflow stream of water through said column, and automatically operating means for decreasing the velocity of said upflow stream upon an increase in density of stratified materials in the water of said column.

13. An apparatus for the separation of materials of different specific gravities comprising, in combination, a sorting column having discharges at different levels for classified materials, means for feeding a mixture of said materials to said column, means for maintaining an upflow stream of water through said column, and automatically operating means for increasing the velocity of said upflow stream upon a decrease in density of stratified materials in said column.

14. An apparatus for the separation of materials of different specific gravities comprising, in combination, a sorting column having discharges at different levels for classified materials, means for feeding a mixture of said materials to said column, means for maintaining an upflowing stream of water through said sorting column, and automatically operating means for decreasing the velocity of said upflow stream upon an increase in density and for increasing the velocity of said stream upon a decrease in density of stratified materials in said column.

15. An apparatus for the classification and separation of materials of different specific gravities comprising, in combination, a water-containing sorting column having discharges at different levels for classified materials, means for feeding a mixture of said materials to said column and for maintaining a continuously upflowing stream of water through said column, and means automatically operating in response to changes in resistance offered by the fluid mass in said sorting column to the passage of the water therethrough to vary the velocity of said upflowing stream.

16. The apparatus as set forth in claim 14 and in which the means for maintaining an upflowing stream of water through said sorting column includes a water supply pipe and a valve therein and in which the automatically operating means for decreasing the velocity of said upflow stream upon an increase in density and for increasing the velocity of said stream upon decrease in density of stratified materials in said column comprises a water-expansion chamber so arranged in open

communication with said sorting column that as the resistance to upward flow of the water through the fluid mass in the sorting column increases and decreases due to increase and decrease in density of said fluid mass by stratification of the materials therein and their settling out therefrom the water respectively rises and falls in said expansion chamber, and mechanism actuated by said rise and fall of the water in said expansion chamber for operating said valve toward closing position to effect said decrease in the velocity of the upflow stream and toward maximum open position to effect said increase in the velocity of the upflow stream.

17. An apparatus for the classification and separation of materials of different specific gravities comprising, in combination, a water-containing sorting column having a lower and an upper discharge for classified materials, means for feeding a mixture of said materials to said sorting column and for maintaining the mixture with the water as a fluid mass, means providing a continuously upflowing stream of water in said sorting column of a velocity causing a hindered settling suspending the material of the lowest specific gravity in delivery relation to said upper discharge, permitting settling of materials of the heaviest specific gravity downwardly to said lower discharge and suspending material of an intermediate specific gravity in said sorting column below said upper discharge, and automatically operating means for intermittently decreasing and restoring said velocity of water upflow in said sorting column to correspondingly decrease and restore the original resistance to downward settling upon increase and decrease in density of said fluid mass in said sorting column so as to prevent the accumulation of said intermediate-specific-gravity material in said column to an extent bringing it into delivery relation with said upper discharge and as to prevent the settling of the lowest-specific-gravity material downwardly to said lower discharge.

18. The apparatus as set forth in claim 17 and in which the means providing an upflowing stream of water in said sorting column includes a water supply pipe under constant head and a valve therein for controlling the velocity of said stream and in which the automatically operating means for intermittently decreasing and restoring the velocity of water upflow comprises a water-expansion chamber so arranged in open communication with said sorting column that as the resistance to upward flow of the water through the fluid mass in the sorting column increases and decreases due to increase and decrease in density of said fluid mass the water respectively rises and falls in said expansion chamber and mechanism actuated by said rise and fall of the water in said expansion chamber for op-

erating said water-control valve toward closing position to effect said decrease in the velocity of the water upflow in said sorting column and toward maximum open position to effect the restoration of the velocity, said mechanism comprising a solenoid and connection between its core and said valve, a circuit and switch for energizing said solenoid, and a float in said water-expansion chamber for actuating said switch.

19. An apparatus for the classification and separation of materials of different specific gravities comprising, in combination, a water-containing sorting column having discharges at different levels for classified materials of different specific gravities, means for feeding a mixture of said materials to said column, mechanical agitating means and hydraulic agitation means for maintaining said mixture with the water as a fluid mass in said column and for the settling classification of said materials according to their differing specific gravities, and means responsive to changes in density of said fluid mass as the materials stratify therein and settle out therefrom for decreasing the hydraulic agitation upon an increase in density and increasing the hydraulic agitation upon a decrease in density of said fluid mass.

20. An apparatus for the classification and separation of materials of different specific gravities comprising, in combination a water-sorting chamber having discharges at different levels for classified materials of different specific gravities, means for feeding a mixture of said materials to said chamber to form a fluid mass with the water therein, means producing a plurality of continuously upflowing currents of water to and in uniform distribution through said fluid mass, and automatically operating means for varying the velocity of said upflowing currents in accordance with the changes in the density of said fluid mass.

21. An apparatus as in claim 20 and in which said means for producing a plurality of upflowing currents of water to and in uniform distribution through said fluid mass includes a perforated plate arranged in said sorting chamber in the path of the water flow to the mixture in said chamber, said plate being designed to allow materials of said mixture to freely pass therethrough.

In testimony whereof I hereunto affix my signature.
